UNITED STATES PATENT OFFICE.

WILHELM WELSCH, OF BERLIN, GERMANY, ASSIGNOR TO GENERAL ELECTRIC COMPANY, A CORPORATION OF NEW YORK.

POTENTIAL-REGULATOR.

1,078,076.

Specification of Letters Patent. Patented Nov. 11, 1913.

Application filed January 5, 1912. Serial No. 669,634.

To all whom it may concern:

Be it known that I, WILHELM WELSCH, a subject of the King of Prussia, residing at Berlin, Germany, have invented certain new and useful Improvements in Potential-Regulators, of which the following is a specification.

My invention relates to the regulation of voltage in alternating current circuits, by means of transformers having separate primary and secondary windings, auto-transformers, or reactances.

It is common to regulate voltage in alternating current circuits by dividing one or more of the windings of a transformer or reactance into groups and varying the number of groups included in the circuit, or circuits, of which the windings are a part. In order to do this, however, without interrupting the supply of energy and without obtaining an injurious short circuiting of a group of turns when cutting one in or out, special appliances or arrangements have been necessary.

By my invention I am enabled to accomplish the above mentioned desirable results without the use of any special appliances and to this end I divide a winding of the transformer or reactance into groups and the core into a plurality of sections and so connect the several groups of windings to each other and to the switching device that in the process of regulating the voltage groups of windings having independent magnetic circuits are cut into or out of circuit, generally alternately, as the switching device is moved. With such an arrangement the switch contacts may be so arranged that the circuit is never interrupted and the short circuitings of the several groups produces no injurious result because a short circuit on one group of the transformer or reactance does not affect the other group or groups which maintain their normal reactance and therefore prevent the current in the short circuited group from rising to an injurious value.

In the drawings which form a part of this specification, I have illustrated two constructions involving my invention.

Figure 1 shows my invention applied to a transformer having separate primary and secondary windings applied to two separate core sections. Fig. 2 shows an auto-transformer or compensator involving my invention.

tion where the single winding is divided into groups placed upon two attached sections of a core. Figs. 3 and 4 indicate the direction of the flux through the various core sections, when the regulator is in normal operation 60 and when one section of a winding is short circuited during the operation of varying the voltage on the circuit respectively.

In Fig. 1, I have shown two separate cores or core sections, 1 and 2. One winding is divided into two sections, 3 and 4, connected in series, and located respectively on the cores 1 and 2. The other winding 5 is divided into two sections, each comprising a plurality of groups which in general are 70 located alternately on the cores 1 and 2. For the purpose of explanation, sections 3 and 4 will be regarded as comprising the primary winding and winding 5 as the secondary. The groups of windings located on the several core sections, while in general including but one group, may include a plurality of groups as is illustrated at 6 and 7. The groups should be so located with respect to the switching device that whenever one group is short circuited there will be between the terminals of the circuit another group located on another core section. Between each two groups is located a fixed contact member 10, and over these are 80 arranged to slide in the usual manner a movable contact member 10¹ which bridges two fixed contact members momentarily as it is moved from one to another. The conductor 11 forms one terminal of the circuit 90 to be regulated. The other terminal is connected to the movable contact member. To vary the voltage in the circuit supplied by the secondary winding 5, more or less groups are cut in or out by shifting the movable 95 contact member. When it is in engagement with any one contact piece 10, the flux through the two cores will be as indicated by the arrows in Fig. 3. To change the engagement of this contact from one fixed contact member 10 to another without interrupting the supply of energy, necessitates that for a certain space of time the movable contact be in engagement with two of the contact members 10, so that the group to 105 which these contact members are both connected will be short circuited. There is, however, no undue current in this group during this time. When this group is short circuited, it acts as a short circuited sec- 110

ondary with respect to the primary winding section 3 or 4, as the case may be, but it has no effect on the other section of the primary winding. We will suppose, for example, that the short circuited section is located on the core 1. During the period of short circuit the impedance of the primary winding section 4 remains constant and hence the current through section 3 and therefore through the short circuited group is limited. Other results are the assumption, during the short circuited period, of the entire load by the windings located on the core 2, as indicated by the working flux diagram in Fig. 4. My invention includes, therefore, the distribution of the regulating coils on a plurality of core sections in such a manner that during the period of time when one winding group is short circuited, another part of the windings on another core section assumes the load and only a restricted amount of current is allowed to be supplied by the short circuited coil.

In Fig. 2, I have shown my invention as applied to an auto-transformer, and in this case the different core sections are indicated by 1 and 2. As in Fig. 1, groups of windings are applied in general alternately to the core sections 1 and 2. I have shown the contact members 10 as located on the central leg of the core, but obviously they may be located wherever desired. The arrows in Figs. 3 and 4 represent the working flux traversing the various sections of the core of this transformer also. In Fig. 2, 12 and 13 indicate the terminals of the auto-transformer winding. The terminal of variable voltage is connected to the movable contact member as before, and the general action of the auto-transformer is similar to the operation of the transformer represented in Fig. 1.

While I have described my invention in transformer constructions, it will, of course, be obvious that it may as well be applied to plain reactance coils; for example, a reactance coil may be constructed similar to the auto-transformer shown in Fig. 2. In this case, however, one side of the circuit would be permanently connected to either 12 or 13, the other side of the circuit being connected

to the contact which is in traveling engagement with the contact members 10.

In certain cases I may find it advisable to make use of more than two core sections, as for example, to render the conditions more favorable as concerns saturation of the magnetic circuits, the essential feature of my invention being that each core section, whatever the number, shall comprise a plurality of winding groups connected in general alternately with similar groups on other core sections. The core sections, it will be understood, may be entirely separate from each other as shown in Fig. 1, or parts of a single piece as in Fig. 2.

What I claim as new and desire to secure by Letters Patent of the United States, is—

1. A potential regulator including a plurality of core sections, a winding divided into groups connected in series, a plurality of the groups being located on each core section, and contact members connected between the groups.

2. A potential regulator including a plurality of core sections, a winding divided into groups connected in series, a plurality of the groups being located on each core section and the first two groups being located on different core sections, and contact members between the groups.

3. A potential regulator including a plurality of core sections, a winding divided into groups connected in series, the groups being located alternately on the core sections with a plurality of groups on each core section, and contact members between the groups.

4. A potential regulator including two core sections, a winding divided into groups connected in series, the groups being located alternately on the core sections with a plurality of groups on each core section, and contact members between the groups.

In witness whereof, I have hereunto set my hand this ninth day of December, 1911.

WILHELM WELSCH.
